UNITED STATES PATENT OFFICE.

CORNELIUS YOUNG, OF SANDY HILL, NEW YORK, ASSIGNOR TO HOWLAND & CO., OF SAME PLACE.

STUFF-REGULATOR FOR PAPER-MACHINES.

SPECIFICATION forming part of Letters Patent No. 312,314, dated February 17, 1885.

Application filed April 15, 1884. (No model.)

To all whom it may concern:

Be it known that I, CORNELIUS YOUNG, a resident of Sandy Hill, in the county of Washington and State of New York, have invented 5 certain new and useful Improvements in Stuff-Regulators for Paper-Machines; and I do hereby declare that the following is a full, clear, and exact description of the invention, that will enable others skilled in the art to 10 to which it appertains to make and use the same, reference being had to the accompanying drawings, and to the letters of reference marked thereon, which form a part of this specification.

15 Similar letters refer to similar parts in the several figures therein.

My invention relates to improvements in stuff-regulators for paper-machines; and it consists in providing an adjustable gate, the 20 movements of which are automatically controlled by the movements of a balanced stuff-chute, and in providing the stuff-box with a vertically-sliding gate.

The object of my invention is to regulate 25 the flow of pulp or "stuff" from the stuff-box to the paper-machine proper.

Figure 1 of the drawings is a plan view of 30 a stuff-box provided with my improved device. Fig. 2 is a vertical section of same taken at broken line $x y$ in Fig. 1. Fig. 3 is a front elevation of same, with part of front wall broken away to show gate I closed. Fig. 4 is same showing gate I open. Fig. 5 is a perspective of gate I and pivoted arms.

35 The box is divided by partitions A, B, and C into four compartments. One of the compartments is provided with one or more apertures, $e e'$, in the bottom, through which the stuff is forced by a pump into the box, until 40 the compartment is filled to the top of partition C, when it flows over between C and D into the next compartment, which retains the stuff until filled to the top of partition B, which extends across the box from block T to 45 block T', the blocks serving to narrow the compartment on the side next the partition B. When this compartment is filled, the stuff flows over partition B, one portion entering the chute H, from which it is conveyed to the 50 paper-machine proper, and the other portion

into the compartment provided with outlet g , through which it flows back to the reservoir from which it was originally pumped into the box. The thickness and weight of paper produced depend upon the thickness 55 and rapidity of flow of stuff to the machine. As the thickness or quality of stuff is not subject to absolute control, uniformity in the weight of paper produced must be secured by subjecting the rapidity of flow to the quality 60 of the stuff. Such control has been heretofore attempted in various ways—by means of valves or adjustable gates controlled by an attendant or by floats and balances.

I make use of an adjustable gate, I, attached 65 to one side of the box by means of the parallel arms $a a'$, which are pivoted one end to the gate and the other end to the block T, so that when the gate is lifted it travels horizontally away from the side of the box to which the 70 arms are pivoted, and when it is allowed to fall it travels toward said side of the box. I also use another adjustable gate, G, supported by rod c , on which it is adapted to slide to and fro between the blocks T T', the lower end of the gate 75 resting upon the upper edge of partition B, or a metallic strip, m , projecting therefrom. The gate is also provided with a threaded arm passing through stop n' , fixed upon rod c , having adjusting-nuts n , by means of which the 80 gate may be secured in different positions. By sliding gate G toward gate I the opening C' is diminished in size, and less stuff will flow to the machine, the opening b' will be increased in size, and more stuff will escape by 85 outlet g . By sliding gate G in the opposite direction toward opening b' more stuff is allowed to flow to the machine and less back to the stuff-reservoir through outlet g . The gate 90 G is therefore first set at the proper point to make paper of the desired weight with a constant flow of the stuff to be used, provided the flow is even in quantity; but experience shows the impossibility of securing such a flow. The pump forces a constant quantity 95 into the box; but the thickness—*i. e.*, the relative quantity of pulp and water—varies continually. When the stuff flows thick, more of it must be held back from the machine, and diverted to the outlet g , and when it flows thin 100

a greater supply must be sent to the machine. This I am able to accomplish by means of the gate I, which is connected by link P with one end of sweep O, the other end of the sweep 5 being connected by link Q and bail R with the chute H at one end, the other end of the chute being hinged upon partition B directly beneath the opening C', so that the stuff which goes to the machine passes through the chute. 10 The weight of the stuff in the chute will depress its projecting end, which raises the gate I and, as before explained, narrows the opening C'. By means of the weight W, adapted to slide upon the sweep O, and the spring S 15 the gravity of the stuff in the hinged chute may be balanced to secure the desired width of opening C'. After the respective parts have been onceadjusted to produce paper of a given weight from a constant flow of stuff of known 20 average quality they will thereafter be automatically adjusted to the varying quality of stuff as the latter passes through and from the stuff-box. If the stuff suddenly thickens, its progress upon the chute is slower, and it 25 dams up, as it were, thereon. The additional weight overcomes the force of the spring S, and the gate I is elevated and forced toward opening C' to close the latter, which forces a larger proportion of the stuff through opening 30 b', and admits a smaller quantity to the chute and machine. If the stuff is thinner than the average, it flows more readily from the chute, leaving a less and lighter quantity thereon, which lowers the gate and widens the opening 35 C' and permits a larger flow of stuff to the chute and machine.

Fig. 3 shows the gate closed to narrow opening C', and Fig. 4 shows the gate opened to widen opening C'.

40 In Fig. 2 I have shown the link Q in two slotted lapping parts, which permits of its longitudinal adjustment by means of the thumb-screw q. The spring S is also attached to its supporting-arm L by a threaded rod, which 45 permits of the adjustment of the spring by thumb-screw t.

I have shown sweep O pivoted at the arm y; but it may be pivoted at arm i instead, through another aperture in the sweep, to 50 change the leverage of chute and gate.

In Figs. 3 and 4 I have shown the supporting-arm d vertically adjustable upon the upright K' by means of set-screw u.

To prevent a sudden rush of thick pulp 55 on the chute, which might cause it to overflow, I provide the partitions D and C, the latter extending from the bottom of the box

upward about half the height of the box, and the former being situated a little one side of the latter and extending both above and below 60 the top of C. It can be slid vertically in grooves V in the sides of the box.

When the stuff is of the usual thickness, it flows through the aperture between D and C, and does not attain a level much above the top 65 of outlet-partition B or m; but if a considerable quantity of thick stuff is suddenly forced into the compartment D' it will not run so freely between D and C, and rises in the compartment D' until the stuff runs thinner, or until 70 its height affords sufficient pressure to force it through the opening.

By raising or lowering the sliding partition D the narrow opening between it and C is lengthened or shortened, which gives it more 75 resistance when lengthened and less when shortened. I am thus able to secure a perfect adjustment of the flow of stuff to the machine automatically and produce an even quality of paper.

What I claim as new, and desire to secure by Letters Patent, is—

1. A stuff-box provided with two outlets, one having a pivoted gate and leading to a paper-machine and the other to the stuff-reservoir, in combination with said pivoted gate, a hinged spring-controlled chute which receives and transmits the stuff in its passage from said box to said machine, a pivoted sweep, and connecting-links by which said chute acts upon said gate, all substantially as described, and for the purposes set forth. 85

2. A stuff-box provided with one or more inlets, e, at or near its bottom, and an outlet, C', about midway between its top and bottom, 95 in combination with fixed partition C, located between said outlet and inlets, extending upward to about the same level occupied by said outlet, the vertically-sliding partition D, slightly removed from partition C, and parallel therewith, and the channel E between said partitions, substantially as and for the purposes set forth. 100

3. In a stuff-box, the combination of an adjustable sliding gate, G, adjustable gate I, a hinged spring-controlled chute, H, lever O, and connecting-links P and Q, substantially 105 as and for the purposes set forth.

In testimony whereof I have hereunto set my hand this 3d day of April, 1884.

CORNELIUS YOUNG.
